1 Claim. (Cl. 114—208)

1

This invention is intended to produce a snag-proof anchor in which the stem is slidable through the body so the hauling rope can exert a pull in a rearward direction which will more easily dislodge a snagged anchor.

In the drawing, Fig. 1 is a section of an anchor; Fig. 2 is a side view; Fig. 3 is a side view in the normal anchoring position; and Fig. 4 is a side view of the anchor in the position assumed when a rearward pull is exerted to dislodge a snagged anchor.

Referring to the drawing, there is shown an anchor having a body comprising a crown 1 provided with flukes 2 attached thereto and a socket 3 in the crown for receiving a cylindrical stem 4 having an eye 5 at its upper end for attachment to a hauling rope. The socket 3 is open at both ends, the opening at the upper end being a rectangular slot 6 lying in a plane transverse to the plane of the flukes through which the stem loosely projects and narrower than a spherical enlargement 7 in the lower end of the stem. With this construction, due to the clearance between the stem and slot the stem is free to swivel in the body of the anchor and to pivot through an angle determined by the length of the slot.

The eye 5 is wider than the widest part of the slot 6 so that once the stem 4 is assembled to the body 1 of the anchor, the stem cannot be disassembled. One way of accomplishing this result is to make the eye 5 narrower than the slot 6 and then to expand the eye, as indicated at 8, so that the expanded eye cannot be drawn back through the slot 6. With this arrangement, the stem may extend out either end of the socket. In the anchoring position, shown in Fig. 3, where a hauling rope 9 attached to the eye 5 exerts an upward pull in the direction of arrow 10, the enlargement 7 is seated against one end of the slot 6 and the greater part of the length of the stem 4 slidably extends out through the other end of the slot. When the anchor is to be released and the hauling rope 9 is pulling in the direction of arrow 11, there is a rearward component of force exerted on the stem 4, which slides the stem through the slot 6 until the enlarged eye 8 is brought into engagement with the opposite end of the slot 6. In this position, the force exerted by the hauling rope 9 will more easily dislodge the flukes 2. This permits the retrieving of anchors which have become snagged and cannot be dislodged by a pull in the same direction as anchoring force. In the anchoring position shown in Fig. 3, the stem 4 is inclined upward. If the anchor is snagged so it cannot be dislodged by a

2

direct pull, the user moves the boat up wind, releasing the tension in rope 9 so the stem 4 falls to a horizontal position. Upon reaching a position up wind of the anchor, a pull on the rope 9 exerts a tension sliding the horizontal stem through the crown of the anchor to the Fig. 4 position where the tension acts directly on the crown and tends to slide the anchor clear of the snagging obstruction.

10 By having the stem 4 slidable through the body of the anchor so that either end of the stem may extend away from the body of the anchor, a single rope may exert a pull in one direction for anchoring (Fig. 3) and in the reverse direction for releasing an anchor which has become snagged (Fig. 4). This result is obtained by providing the stem with enlargements at both ends so that either end may project from the body of the anchor.

20 What is claimed as new is:

In an anchor having a body comprising a crown and flukes attached thereto with a socket in the crown open at both ends, the opening at one end of the socket comprising a slot, said slot lying in a plane transverse to the plane of the flukes, a stem slidably projecting through the slot and having at opposite ends enlargements larger than the slot and retained therein by the enlargements at opposite ends whereby the stem may slide through the slot and out either end of the slot with part of the stem always retained within the slot, said slot having a clearance between it and the stem permitting free swinging of the stem between an inclined position in normal anchoring position and a horizontal position when the anchoring pull on the stem is released, and one of the enlargements comprising an eye for attachment to a hauling rope and the other of the enlargements being smaller than the socket, the tension in the rope in the anchoring position pulling the other enlargement into engagement with one end of the slot and the stem falling to a horizontal position upon release of the tension of the rope and the rope pulling the stem through the slot as the rope is pulled in the reverse direction to release the anchor from an obstruction.
